[57] CLAIM

The ornamental design for a signalling light to warn trailing drivers of high beam usage, as shown and described.

DESCRIPTION

FIG. 1 is a perspective view of a signalling light to warn trailing drivers of high beam usage showing my new design;

FIG. 2 is a front elevational view thereof;

FIG. 3 is a rear elevational view thereof;

FIG. 4 is a right side elevational view thereof, with the opposite side being a mirror image, and with the cord broken away to indicate indeterminate length;

FIG. 5 is a top plan view thereof; and,

FIG. 6 is a bottom plan view thereof.

FIG.1.

FIG. 2

FIG. 4.

FIG. 3.

FIG. 6.
